UNITED STATES PATENT OFFICE.

FLORENCE OHR, OF NORMAL, ILLINOIS.

PIANO-STOOL.

SPECIFICATION forming part of Letters Patent No. 315,323, dated April 7, 1885.

Application filed November 24, 1884. (No model.)

To all whom it may concern:

Be it known that I, FLORENCE OHR, of Normal, in the county of McLean and State of Illinois, have invented certain new and useful 5 Improvements in Piano-Stools, of which the following is a full, clear, and exact description, reference being had to the accompanying drawings, forming part of this specification, in which—

10 Figure 1 is a vertical sectional view of my improved piano-stool. Fig. 2 is a perspective view of the interior box or receptacle for the sheet-music.

15 Similar letters of reference indicate corresponding parts throughout the drawings.

My invention is an improvement in piano-stools; and it consists in a stool provided with a receptacle in its seat, in which sheet-music may be placed.

20 My invention further consists in the peculiar construction, arrangement, and combination of the several parts, all of which I shall hereinafter fully describe, and specifically point out in the claims.

25 In the said drawings, A represents the piano-stool standard, which may be of any well-known construction, and ornamented to suit the taste of the public. This standard is provided with the usual means for receiving the screw B, secured to the bottom of the seat.

30 In the construction of piano-stools now in general use the seat in many cases is simply a cushion, and the sheet-music has often been placed upon the piano, or a table or other separate and independent device. By the construction herein shown I am enabled to provide a means which, to a great extent, obviates this difficulty and permits the operator to always have his music within ready reach.

35 40 This is accomplished by having the seat formed in the similitude of a box, C, properly upholstered, and provided with a hinged side, D,

which is adapted to swing downward to permit the operator to reach the interior of the seat. Within the seat I prefer to place a receptacle, E, provided with an open end, e, through which the music-sheets are inserted. A strap, F, or its equivalent, attached to the receptacle, furnishes a ready means for withdrawing the receptacle from the seat, and the 50 sheets of music can be easily removed from the receptacle E through its open end. When the desired sheet of music has been removed, the receptacle, with such other music not needed, can be inserted in the seat and the 55 hinged side D closed. I am thus enabled to construct a cheap and substantial stool, and one that will prove of great benefit to musicians, while the hinging of the side D and the 60 insertion of the receptacle do not affect the 65 exterior appearance of the device in the least.

Having thus described my invention, what I claim as new, and desire to secure by Letters Patent, is—

1. In a piano-stool, the combination, with 65 the standard A and screw B, of a seat, C, provided with a downwardly-swinging side, D, a removable receptacle, E, within the seat, the 70 said receptacle having closed top and sides, and an open end, through which the sheet- 75 music is inserted, as herein set forth.

2. In a piano-stool, the seat C, provided with a hinged side, D, in combination with the receptacle E, having an open end, e, and a strap, F, substantially as and for the purpose described.

In testimony that I claim the foregoing I have hereunto set my hand this 30th day of October, 1884.

FLORENCE OHR.
